UNITED STATES PATENT OFFICE

JOHN J. BERTORELLO, OF MONTROSE, COLORADO, ASSIGNOR TO ALEX BOYER, OF DELTA, COLORADO

UNIVERSAL MARKER

Application filed May 27, 1930. Serial No. 456,164.

The present invention relates to marking devices and more particularly to a universal marking device for marking the ground so as to determine the position for planting of various articles therein.

An object of this invention is to provide a device of this character which is so constructed that it is readily adjustable so as to permit the marking of pairs of rows of various widths.

Another object of this invention is to provide a marker which is so constructed that the earth or dirt turned up by the digging or cultivating blade will be thrown to either side of the ditch or channel from which point it may be readily dragged or raked into the channel when the seed has been planted therein.

A further object of this invention is to provide a marker which is so constructed as to permit the independent adjustment of the marking members with respect to the wheels and to permit the lateral adjustment of the wheels on the frame so that they may be positioned either directly in front of the markers or to either side thereof.

A still further object of this invention is to provide an adjustable or swingable shovel member which is adapted to throw the dirt to either side of the row formed by the marking blade.

Another object of this invention is to provide a device which is so constructed as to be able to dig furrows or ditches for irrigation or other purposes where a relatively wide ditch is required.

The above and various other objects and advantages of this invention will in part be described in and in part be understood from the following detailed description of the present preferred embodiment, the same being illustrated in the accompanying drawings wherein:

Figure 1 is a detail top plan view of a device constructed according to the preferred embodiment of this invention;

Figure 2 is a detail side elevation of the device partly in section for greater clarity;

Figure 3 is a fragmentary side elevation partly in section of the marking frame; and

Figure 4 is a sectional view taken on the line 4—4 of Figure 2.

Referring to the drawings wherein like numerals of reference designate corresponding parts throughout the several views, the numeral 10 designates generally a frame which comprises an inner U shaped member 11 and an outer U shaped member 12 which are bolted or otherwise secured to a forwardly extending tongue or bar 13.

The U shaped frame members 11 and 12 preferably extend rearwardly, and a transversely disposed axle or shaft 14 is secured to the free ends of the U shaped member 12, the U shaped member 12 being provided at the outer end portions thereof with bearings 15 which are preferably formed integrally with the frame, the frame member 12 being preferably constructed of a piece of bar metal and the bearings 15 being formed by bending the outer ends of the bar so as to form an eye or bearing member 15.

The intermediate or inner frame member 11 is provided with bearing members 16 for engagement with the shaft 14. The free ends of the inner and outer frame members 11 and 12 are preferably disposed in spaced relation to each other and a wheel 17 is rotatably positioned on the shaft 14 intermediate the free ends of the frame members 11 and 12. A pair of adjustable collars or rings 18 are positioned on the shaft 14 and engage against each end of the hubs of the wheels 17 so as to hold the wheels in adjusted position.

A seat 19 is secured to the upper end of a supporting post 20 which is bolted or otherwise secured to the centrally disposed member 13.

The free ends of the inner frame member 11 are secured together by means of a transversely disposed bar 21 which is secured by means of bolts or rivets at the opposite ends thereof to the free ends of the inner frame member 11.

A pair of L shaped members 22 are secured at one end to the shaft 14 and if desired may be bolted, riveted or welded to the shaft and the opposite ends or legs of the L shaped members 22 are adapted to extend outwardly and are secured at the outer end portions

thereof to a rearwardly extending bar 23 which is provided at the rear end portions thereof with an inwardly extending flange or lug 24, the lug 24 being bolted or otherwise secured to the outer end of the L shaped member 22 by means of bolts 25 or the like.

The outwardly extending leg 26 of the rear frame member 22 is provided with a rearwardly extending apertured plate 27, the plate 27 having a plurality of spaced apertures 28 therein for adjustably receiving a marker supporting member 29, the marker supporting member 29 being provided with a pair of spaced horizontally extending arms 30 which are adapted to be positioned on the upper and lower faces of the plate member 27 and adjustably secured thereto by means of bolts 31 or the like.

The longitudinally disposed leg 32 of the rear frame members 22 preferably extends rearwardly from the plate 27 as indicated at 33, and a transversely positioned supporting bar 34 is secured to the outer end of the rearward extension 33. The outer end of the member 34 is preferably free, and the member 34 preferably provides an additional support for the adjustable marker frame 29.

The marker frame 29 is preferably formed on an arc and is provided with a longitudinally extending slot 35 so as to adjustably receive adjacent the lower end portion thereof an adjustable marker blade 36 which may be of any desired configuration, the blade 36 being adjustably secured to the frame 29 by means of bolts 37 or the like, the bolts 37 engaging U shaped plate members 38 which engage against the periphery of the segmental member 29 so as to prevent spreading or opening of the slot 35.

A shovel or spreading member 39 is secured by means of bolts 40 or the like to an upstanding slotted support 41 which is pivotally secured at the lower end thereof by means of bolts 42 to the segmental frame 29 and the upper end of the supporting member 41 is adjustably secured to a rearwardly extending bar 43, the bar 43 being provided with a plurality of spaced apertures 44.

The forward end of the bar member 43 is preferably bent downwardly and engages in a plate 45 which is secured to the periphery of the segmental frame member 29 by means of an eye bolt 46, the eye bolt 46 also engaging the transversely disposed member 34 so as to prevent lateral swinging movement of the marker frame 29.

It will be understood that the plate member 45 may be adjustably positioned on the periphery of the segmental frame 29 and if desired the plate member 45 may be provided with a plurality of apertures 47 or the like so that the downwardly extending forward end of the bar 43 may be adjustably positioned in the plate 45.

A transversely disposed shaft 48 is mount-

ed in bearings 49 carried by the inner frame member 11, and an upwardly extending lever 50 is secured to the rockable shaft 48, the lever 50 engaging a toothed rack 51 which is mounted on the inner frame member 11 so as to lock the shaft 48 in the desired position. The outer ends of the shaft 48 are provided with arms 52 and a pair of link members 53 are secured at one end to each arm 52 and at the opposite end are rockably secured to a forwardly extending lever or arm 54, the arm 54 being fixedly secured at the rear end thereof to the rearwardly extending frame member 22 as at 55.

In the operation of this device, the wheels 17 may be positioned on the shaft 14 in the desired location with respect to the marking members 36, that is, they may be either positioned in alignment with the marking members 36 or outwardly or inwardly therefrom.

The marking frame members 29 may be secured to the plate 27 in the desired aperture 28 thereof and the lever 50 may be rocked so as to swing the member 54 forwardly and upwardly, the rocking movement of the bar 54 swinging the marking frame 29 downwardly into contact with the ground.

When the device is moved or drawn forwardly, the marking member 36 will dig a channel or ditch and the spade or shovel member 39 will cooperate with the marking point 36 so as to provide the desired width of ditch into which suitable seeds or plants may be placed. The rear shovel member 39 may be adjusted by means of the adjusting bar 43 so that any vertical adjustment may be made so as to throw the dirt outwardly of the channel to the desired degree.

It will be obvious from the foregoing that a substantial adjustable marking device has been disclosed by means of which a pair of channels or ditches may be formed in the ground, the channels being of any desired width and any desired distance apart depending only on the capacity of the marker.

It will, of course, be understood that various changes and modifications may be made in the details of construction and design of the above specifically described embodiment of this invention without departing from the spirit thereof, such changes and modifications being restricted only by the scope of the following claims:—

What is claimed is:

1. A universal marker of the character described comprising an inner and an outer frame member, a transversely disposed shaft secured to said frame members, a pair of wheels rotatably mounted on said shaft, a pair of collars mounted on said shaft and engaging against the opposite ends of the hubs of said wheels whereby to adjustably position said wheels upon said shaft, a pair of rearwardly extending frames secured to said shaft, an outwardly extending plate secured

- to each of said frames intermediate the ends thereof, said plate having a plurality of spaced apertures therethrough, a segmental slotted marker frame adjustably positioned on said plate, a forwardly extending arm secured at the rear end thereof to said rearwardly extending frames, adjustable rocking means secured to the forward end of said forwardly extending arm, and a pair of marker members adjustably positioned on said marker frame.
2. A marker of the character described comprising a pair of rearwardly extending U shaped frame members, a transversely disposed shaft secured to said frame members, adjustably mounted wheels positioned on said shaft between said frame members, a marker frame supporting member secured to said shaft and extending rearwardly thereof, a segmental marker frame adjustably secured to said supporting member, means carried by one of said U shaped frame members whereby to adjustably swing said supporting member, a marking blade secured to said marker
- 5 10 15 20 25
- frame, and an adjustably secured spreading member secured to said marker frame and positioned rearwardly thereof.
3. A marker of the character described comprising an inner and an outer U shaped rearwardly extending frame member, a transversely disposed shaft secured to the free ends of said frame members, wheels adjustably mounted on said shaft, a pair of rearwardly extending frames secured to said shaft adjacent said inner frame members, an outwardly extending apertured member secured to each of said latter frames intermediate the ends thereof, a segmental marker frame adjustably mounted on each of said outwardly extending plate members, bracing means for said marker frames, means for rocking said rearwardly extending frames, a marking blade secured to each of said marker frames, and means for adjustably mounting a shovel on each of said marker frames.
- 20 25 30 35 40
- In testimony whereof I hereunto affix my signature.

JOHN J. BERTORELLO.
